(57) **CLAIM**

The ornamental design for a post and head unit for a jewelry kit assembly as shown and described.

DESCRIPTION

FIG. 1 is an exploded plan view of post and head unit for a jewelry kit assembly;

FIG. 2 is perspective view of the post component of FIG. 1;
FIG. 3 is a front view of the post component of FIG. 2;
FIG. 4 is a top view of the post component of FIG. 2;
FIG. 5 is a bottom view of the post component of FIG. 2;
FIG. 6 is a perspective view of the head unit component of FIG. 1;

FIG. 7 is a front view of the head unit component of FIG. 6;
FIG. 8 is a bottom view of the head unit component of FIG. 6;

FIG. 9 a top view of the head unit component of FIG. 6; and,
FIG. 10 is an exploded perspective depicting the post and head unit for a jewelry kit assembly of FIG. 1.

The broken lines shown in the drawings illustrate portions of the post and head unit for a jewelry kit assembly that form no part of the claimed design.

1 Claim, 4 Drawing Sheets
